UNITED STATES PATENT OFFICE

2,227,091

INKSTAND

Laurence W. Kendrick, Wellesley, Mass., assignor
to The Carter's Ink Company, Cambridge, Mass.,
a corporation of Massachusetts

Application March 26, 1940, Serial No. 325,997

4 Claims. (Cl. 120—64)

The invention relates to that type of inkstand in which the ink is raised from out of the body of the stand into a dip-well, into which the pen is dipped, by compression of air within the ink containing chamber of the stand through distortion of an elastic diaphragm; and, after the filling of the dip-well, atmospheric air is restored through a vent opening to the chamber of the stand for breaking the partial vacuum therein attending the return of the diaphragm to its normal shape, the vent opening being closed during the period that the air within the ink chamber is under compression.

Among the objects of the invention are:

15 To provide a dust closure for the dip-well; and especially one that will prevent the escape of ink in case the stand is overturned;

20 To provide means for obtaining guidance of the pen into the dip-well; and also means for limiting the amount of the pen's insertion into the dip-well;

25 To provide means by which the diaphragm may be distorted by manual pressure upon the pen holder; and

30 To provide means for automatically closing the port opening between the chamber of the inkstand and the atmosphere preliminary to the time that the diaphragm is distorted for compressing the air within the inkstand; and for automatically clearing the opening to the atmosphere for breaking the vacuum upon the return of the diaphragm to its normal shape.

The invention can best be seen and understood by reference to the drawing in which:

35 Fig. 1 is a plan of an inkstand embodying the invention.

Fig. 2 is a view in cross section.

Fig. 3 is a cross section showing the normal disposition of the parts.

40 Fig. 4 is a cross section showing the disposition of the parts during the filling of the dip-well.

Fig. 5 is a fragmentary view in side elevation of a modified construction.

45 Referring to the drawing 1 represents a common type of ink bottle having an externally threaded neck 2 on which fastens a screw cover (not shown).

It is the body of the bottle which forms the ink containing body of the ink well, the original cover having been removed and replaced by an attachment as will now be described.

50 Resting upon the top edge of the neck 2 of the bottle, or stand, is a disc of elastic material, such as rubber, forming a diaphragm 3. The diaphragm is clamped to the neck along its edge

portion resting upon the neck, by a clamp 4. This clamp screws on to the threads of the neck like the removed cover. In fact the clamp is like the removed cover, excepting that it is provided with a central opening 5.

Thus fastened the diaphragm 3 will close the ink containing chamber of the bottle, except for a vent opening to the atmosphere later to be referred to. On account of its elasticity the unclamped central portion of the diaphragm may be displaced or distorted axially in the direction of the chamber of the bottle compressing the air therein, assuming the vent opening to the atmosphere previously referred to is closed.

At its center the diaphragm is provided with a 15 sunken frustro conical socket 6. Below this socket is located a dip-well 7, the bottom of the socket being open to the dip-well. The side wall of the socket has an opening 8 through it which is the vent opening to the atmosphere from out of the 20 chamber of the stand previously referred to. Arranged alongside the dip-well and opening into its top is a tube 10 which extends downwardly to the bottom of the bottle or ink containing stand. The socket, dip-well and tube are all preferably made 25 of rubber molded integral with the diaphragm.

Located upon the upper side of the diaphragm in cooperation with it and the dip-well is an element 12, which, like the diaphragm and associated parts, is made of rubber. The body 13 of this element is generally tubular in form, with bottom 14 made conical to conform to the general contour of the socket 6 in the diaphragm within which it is contained.

The conical end 14 of the element normally fits 35 rather loosely within the socket 6, and when the end of the element is thus contained the body of the element extends upwardly through the central opening 5 in the clamp 4, rising well above the clamp which forms a frame around the element. 40 The arrangement of the element is also preferably such that its body extending through and rising above the clamp will occupy a normal position inclined from the vertical.

The element is maintained in the normal position just referred to, with the bottom end thereof contained within but clear of the socket 6 in the diaphragm, by hinging it to the diaphragm by vulcanizing along the edge portion 15 thereof.

50 To limit the upward extension of the element through the opening in the clamp, and for preventing its being pulled through the opening, the element is preferably provided with a flange 16, which, when the element is in its normal position 55

of rest, engages the under side of the clamp around the opening in it.

On the inside the element is provided with an annular shoulder 17. Above this shoulder, reaching to the top end of the element, its bore 18 is of sufficient size to receive the end portion of a pen holder *a*, bearing a pen *b*, the handle being inserted into the element until its end engages the shoulder. With the handle thus contained, the pen *b* extends through the bore 19 of the element and which is of sufficient size to admit of the passage of the pen. The bottom end of the element is closed except that it is crossed by slits 20 which permit the passage of the pen through it. The relation between the dip-well and the shoulder 17 in the element is such that when the end of the pen handle is engaging the shoulder, the pen, having passage through the bottom of the element, will extend a proper distance into the dip-well.

With the element thus formed and arranged it will primarily function as a holder for the pen and its carrying handle when not in use, the handle being simply introduced into the element and brought to rest against the annular shoulder 17 therein. When the pen is used the element will act as a guide for the pen into the dip-well, and will limit the amount of the pen's insertion into the dip-well, which is determined by the annular shoulder inside the element against which the end of the pen carrying handle has engagement. The normally closed bottom end of the element will lie just above the dip-well and accordingly will function as a dust closure for it, and will prevent the escape of ink in case the stand is overturned. For introducing ink into the dip-well from out of the main ink chamber or reservoir of the bottle or stand the pen handle is brought into contact with the interior shoulder 17 of the element and thereupon by manual pressure asserted upon the element through the handle, the element will be appreciably depressed, the first action being to bring the bottom end of the element into contact with the interior wall of the socket 6 in the diaphragm, thus closing the vent opening 8 in the wall of the socket from the atmosphere. Thereupon, if the pressure be continued the diaphragm is downwardly distorted, thus compressing the air within the ink containing chamber or body of stand, whereupon the ink will be forced up through the tube 10 and pass into the dip-well. This action may be repeated if the dip-well is not filled with the first operation. When the filling of the dip-well is complete pressure upon the element is relieved thereby allowing the diaphragm to resume its normal shape and the lower end of the element to rise clear of the socket in the diaphragm within which it is contained, thus clearing the vent opening 8 to the atmosphere and breaking any partial vacuum that is formed within the ink chamber attending the return of the diaphragm to its normal shape. This vacuum if not broken might act to draw the ink out of the dip-well back through the tube.

In Fig. 5 a slight modification is shown in that the element is not attached or hinged to the diaphragm. Instead the element is fastened to the clamp, and this by providing the element with annular incision 21, into which fits the edge of the clamp around the opening 5 in it, while above the element is provided with an annular flange or bead 23, which laps over on to the upper side of the clamp. The element is thus secured to the clamp with capability of turning thereon. The general form of this modified structure is the

same as before, and its functional operation is substantially the same.

The element will nominally be so positioned that its bottom end will lie contained within the socket 6, in the diaphragm, but clear of the vent opening 8, therein.

When it is desired to fill the dip-well the lower end portion of the element is brought into contact with the wall of the socket, closing the vent opening and distorting the diaphragm by pressure exerted through the pen holder upon the element, which tends to distort the lower end portion of the element which is made of rubber sufficiently elastic to permit of this distortion. When the pressure is relieved the parts will return to their normal position.

I claim:

1. In an inkstand the combination comprising a body with ink holding chamber, a flexible diaphragm maintained in air tight relation to said chamber for compressing air therein on distortion of said diaphragm, said diaphragm having a socket with vent opening therein, a dip-well in open connection with said socket, a tube leading to said dip-well from out of said chamber, an element arranged above said socket with aperture therein for receiving the end of a penholder and admitting of the passage of the pen there-through into said dip-well through said socket, means for normally maintaining said element out of contact with said socket and vent opening therein, and means whereby said element may be brought into engagement with said socket closing said vent opening and distorting said diaphragm through manual pressure upon said element by said pen holder.

2. In an inkstand the combination comprising a body with ink holding chamber, a flexible diaphragm maintained in air tight relation to said chamber for compressing air therein on distortion of said diaphragm, said diaphragm having a vent opening, a dip-well integrally connected to said diaphragm and in open communication with the space above said diaphragm, a tube leading to said dip-well from out of said chamber, an element arranged above said diaphragm with aperture therein for receiving the end of a pen holder and admitting of the passage of the pen there-through into said dip-well, means for normally maintaining said element out of contact with said diaphragm and vent opening, and means whereby said element may be brought into engagement with said diaphragm, closing said vent opening and distorting said diaphragm through manual pressure upon said element by said pen holder.

3. In an inkstand the combination comprising a body with ink holding chamber, a flexible diaphragm maintained in air tight relation to said chamber for compressing air therein on distortion of said diaphragm, said diaphragm having a vent opening, a dip-well integrally connected to said diaphragm and in open communication with the space above said diaphragm, a tube leading to said dip-well from out of said chamber, an element arranged above said diaphragm with stepped aperture there-through and shoulder arranged for receiving the end of a pen holder to engage said shoulder and admitting of the passage of the pen borne by said holder there-through into said dip-well, means for normally maintaining said element out of contact with said diaphragm and vent opening, and means whereby said element may be brought into engagement with said diaphragm closing said vent opening and distorting

said diaphragm through manual pressure upon said element by said pen holder.

4. In an inkstand the combination comprising a body with ink holding chamber, a flexible diaphragm, a clamp attachable to said body for maintaining said diaphragm in air tight relation to said chamber for compressing air therein in distortion of said diaphragm, said diaphragm having a socket with a vent opening therein, a dip-well connected to said socket and in open communication therewith, a tube leading to said dip-well from out of said chamber, an element arranged above said socket with extension through said clamp, said element having a

stepped aperture through it with shoulder arranged for receiving the end of a pen holder to engage said shoulder and admitting of the passage of the pen borne by said holder therethrough into said dip-well through said socket, means for normally maintaining said element out of contact with said socket and vent opening therein, and means whereby said element may be brought into engagement with said socket closing said vent opening and distorting said diaphragm through manual pressure upon said element by said pen holder. 5 10
